UNITED STATES PATENT OFFICE.

DAN McGEE, OF FORT WORTH, TEXAS.

AEROPLANE.

1,400,490.

Specification of Letters Patent. Patented Dec. 13, 1921.

Application filed April 25, 1921. Serial No. 464,074.

To all whom it may concern:

Be it known that I, DAN McGEE, a citizen of the United States, residing at Fort Worth, in the county of Tarrant and State of Texas, 5 have invented new and useful Improvements in Aeroplanes, of which the following is a specification.

The object of my present invention is the provision of an aeroplane embodying simple, 10 inexpensive and easily installed manually-controlled means whereby its aviator is enabled to prevent the aeroplane from going into a tail spin.

To the attainment of the foregoing, the invention consists in the improvement as hereinafter described and definitely claimed.

In the accompanying drawings, forming part hereof:

Figure 1 is a plan view of so much of an 20 aeroplane as is necessary to illustrate the application of my improvement.

Fig. 2 is a side elevation of the same.

Fig. 3 is a detail longitudinal vertical section illustrative of the manner in which the 25 horizontal control is horizontally connected with the wing of the aeroplane.

Similar numerals of reference designate corresponding parts in all of the views of the drawings.

30 The fuselage 1 of the aeroplane is provided at its rear end with a rigid stabilizer 2 and a rigid longitudinal vane 3.

The wing 4 of the aeroplane is recessed as indicated by 5, and arranged to work in the 35 said recess 5 is the horizontal control 6 of my improvement; the said horizontal control 6 being hingedly connected to the wing 4 at the points 7, as shown in Fig. 1. Fixed to the hinged portion of the horizontal control 40 6 is a pendent arm 8 that merges at its lower end into a handle 9 arranged within convenient reach of an aviator disposed in the cock pit 10. Manifestly by manipulating the handle 9 the aviator is enabled to swing the control 6 so as to direct the aeroplane 45 either upwardly or downwardly as occasion demands.

Superimposed on and fixed to the forward portion of the fuselage 1 is a frame 11, and pivoted between the top of the said frame 50 and a bearing 12 on the fuselage is a horizontally swinging rudder 13. The said rudder 13 is provided with a rearwardly directed handle 14 which also reaches to a point within convenient reach of an aviator in the 55 cock pit 10. From this it follows that by manipulating the handle 14 the aviator is enabled to direct the aeroplane either to the right or the left.

By virtue of the fuselage 1 having the 60 rigid stabilizer 2 and vane 3 and being equipped with the control 6 and the rudder 13 relatively arranged as defined to the fuselage 1 and the wing 4, it will be apparent to those skilled in the art that the aviator of the 65 improved aeroplane is enabled to effectively prevent the same from going into a tail spin, it being noted in this connection that the said result is brought about by the aviator's manipulation of the control 6 and the rudder 13. 70

Having described my invention, what I claim and desire to secure by Letters-Patent, is:

An aeroplane comprising a fuselage having at its rear end a rigid stabilizer and a 75 rigid vane, a wing fixed with respect to the fuselage and having a recess in its rear edge, a vertically swinging horizontal control hinged to the wing and movable in said recess and having a pendent arm on which is 80 a rearwardly directed handle, a frame superimposed on the forward portion of the fuselage, and a horizontally swinging rudder pivoted between the top of said frame and the fuselage and having a rearwardly directed 85 handle; the said fuselage being also provided with a seat for an aviator, and the handles being arranged in close proximity to said seat.

In testimony whereof I affix my signature. 90

DAN McGEE.
